Des. 650

Charles Chinnock of New York, N.Y.
Letters Patent No. 650 Dated May 23rd 1834.

The schedule referred to in these Letters Patent is making part of the same.

To all whom it may concern:

Be it known that I, Charles Chinnock, of the City, County, & State of New York, have invented a new ornamental design for Cast Metal Clock Case fronts, which I denominate the "Pillar" pattern; and I do hereby declare that the following is a full, clear and exact description of the same, reference being had to the accompanying drawings forming part of this specification, in which-

Fig. 1 is a front view of a clock case front of my design.

Fig. 2 is a side profile of the same.

Fig. 3 is a vertical section through the center, and

Fig. 4 a horizontal section through the opening for the clock face.

Similar letters of reference indicate the same parts in the different Figs.

The sides of the front are formed by two semi-octagonal pillars

AA, having bases BB composed each of two beads, and having beads a, b &c. and capitals d. The upper part of the center between the pillars is nearly flat being very slightly convex and has an ovolto shaped border g. at the top and sides, which unites with the mouldings a, b, c. but not with the parts of the pillars between the said mouldings. The lower part of the center is bowed outwards in front of the upper part, and arched over the small opening C, where the pendulum is adjusted, and has a sunk panel e. The lower part of the center, and the ovolto shaped border of the upper part rise from the upper part with a slope f. The whole front is composed of one plate cast as thin as practicable in all parts.

What I claim as my invention & desire to secure by Letters Patent
is, the design & configuration of the clock case front, as represented in the accompanying drawings
and herein described and denominated the "Pillar" pattern.

Witnesses:-

J. W. Fenton,
W. H. Stogdill.
